UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

TYPE SETTING AND DISTRIBUTING MACHINE.

1,076,640.

Specification of Letters Patent.

Patented Oct. 21, 1913.

Application filed January 10, 1906. Serial No. 295,332.

To all whom it may concern:

Be it known that I, HENRY C. OSBORN, a citizen of the United States, residing at Cleveland, in the county of Cuyahoga and State of Ohio, have invented a certain new and useful Improvement in Type Setting and Distributing Machines, of which the following is a full, clear, and exact description, reference being had to the accompanying drawings.

One of the objects of this invention is to provide a simple and efficient copy holder and indicator, for use in assembling or distributing type, which will show the individual character about to be assembled or distributed. The invention is thus well adapted for use with a combined typesetting, distributing and printing machine, as shown in Patent No. 722,404, issued March 10th, 1903, to H. C. Gammeter. Such a machine includes a supply drum, a printing drum, each adapted to carry rows of type on its surface, and a passageway between them, the type being stored in rows of the same letter on the supply drum and being adapted to be passed one at a time onto the printing drum, to assemble words, and, after the printing, distributed to the supply drum.

The present invention provides an indicator for both the assembling and distributing, which, as shown, comprises a copy holder adapted to carry a copy of the matter to be assembled or distributed and a cooperating pointer carried by a follower block which advances with the type. This arrangement is adapted to indicate to the operator the character on the individual type to be transferred to or from the supply drum, whereby he is enabled to quickly set the supply drum to have its proper channel in position to receive the type.

The invention is more fully hereinafter described and its essential characteristics set out in the claims:

In the drawings, Figure 1 is a front elevation of a duplicating machine including two drums and a transfer mechanism between them. Fig. 2 is a vertical cross section on a plane taken between the supply drum and the central frame plate, and showing the transfer mechanism and the copy holder. Figs. 3 and 4 are front elevations of the comb mechanism which operates to feed the type toward the transfer channel, Fig. 3 being the left-hand portion of such mechanism

and Fig. 4 the right hand portion. Fig. 5 is a horizontal section on the line 5—5 of Fig. 2. Fig. 6 is a fragmentary rear elevation showing the copy holder and a portion of the printing drum. Fig. 7 is a vertical section substantially on the line 7—7 of Fig. 2, being in a plane parallel with Fig. 1 and looking toward the front of the machine. Figs. 8, 9 and 10 are details of the follower block which comes into action in advancing the type. Fig. 11 is a diagram representing the course of the cable which operates the supply drum indicator. Fig. 12 is a perspective view of the type employed in the machine.

In order that the operation of my indicator will be better understood, I will first describe the arrangement of the type drums and the transfer of type from one to the other, though these features are the invention of H. C. Gammeter and described in his application No. 298,121 filed Jan. 27th, 1906, and claimed in that application and more broadly in his prior application Serial No. 236,463, filed December 12th, 1904. The disclosure herein of mechanism in addition to my copy holder not claimed herein is not intended as, in any sense, a dedication thereof, for all patentable features of the same are believed to be covered in pending applications.

The supply drum, as a whole, is designated A and the printing drum B. These are arranged so that the type ordinarily stored on the supply drum may be transferred as desired to the printing drum, a preferable arrangement being that shown in the drawings, wherein the drums are of the same diameter and are placed with their axes in alinement. Each drum has a series of similar longitudinal type holders which may be channels contracted at their outer edges to overhang the type and hold them in place. The drums are mounted on alined shafts, (not shown), which have bearings respectively in the end frame standards Z and Z', and each in the bushing z in the intermediate frame plate Z^2 . The drums are provided with cranks a' and b' respectively by which they may be rotated, the supply drum being rotated to bring the proper channel into position for transfer of the type from one drum to the other; the printing drum, after assemblage of the type, being rotated to cause the printing. The printing drum is shown as having a recess b^2 in which is

mounted a pair of spools D D' which are adapted to carry an inking ribbon which is passed around the drum after the type are assembled to ink the same and enable them to print on paper drawn between the printing drum and the impression platen E. (Fig. 1,) geared with the drum by gears e and d.

On the upper edge of the central frame member Z² are a pair of blocks z' and z² which are separated and are formed at their opposed faces with ribs corresponding to the grooves X' in the type X, whereby these blocks provide a transfer channel z³ from one drum to the other.

15 The operator causes the transfer from one drum to the other by the depression of either of a pair of finger keys f', f². These keys are formed on the ends of a lever f which is rigidly mounted on a rock shaft F which is journaled in the frame plate Z². At the rear end of this rock shaft is a segmental gear f⁴ which meshes with a beveled pinion g on a vertical shaft G which is journaled in frame standard Z² and the bracket z⁵ carried thereby. On the shaft G, near its upper end, is formed a head g' having a pair of projecting lugs g². Above the transfer channel z³ are a pair of stationary plates z⁷ and z⁸ which extend lengthwise over the two drums. Between these plates are a pair of combs H' and H² having teeth on their lower sides and having on their upper sides inclined lugs h which engage with recesses in bars h² which are allowed a limited sliding movement between the stationary plates. Links h⁶ connect with the inner ends of the bars H' and H² and have toes extending rearward into the path of the lugs g² on the head g'. Friction retards the bar h² wherefore the comb, when drawn inward, slides downward before the bar moves. When the comb reaches its limit of downward movement, the continued rotation of the head g' moves forward both the comb and bar.

45 When the finger pressure is released on the key, the spring h⁷ engaging the links h⁶ causes the displaced comb to travel upward and then backward.

In the channels of the supply drum behind the type are followers J which the teeth of the comb H' are adapted to engage. Above the printing drum is a follower block K slidably guided on the plates z⁷ and z⁸ near their lower edges and having teeth 50 which the comb H² is adapted to engage, this block having a pivoted pawl k which may engage behind the type in the printing drum. The actuation of either key therefore is to cause the row of type in the channel of the corresponding drum, which is opposite the transfer channel, to be moved toward that channel, the foremost type passing into the channel. The succeeding actuation of the key again advancing the line of 55 type, shoves another type into the channel,

advancing farther the type already therein so that the type thus pass through the transfer channel into the channel of the opposite drum.

It is essential that for each actuation of the key, the engaged type line be advanced just the thickness of a type so that but one type at a time will be transferred. To accomplish this, I provide a limiting finger which enters the transfer channel every time a type is introduced therein and is allowed a movement with the type just equal to the width of that type, thereby preventing oversetting and restricting the advancement of the desired amount. The mechanism shown for this purpose comprises a finger L located beneath the type channel and forked around a bushing N on the shaft F. An arm n rigid with this bushing carries a roller n' occupying a slot l in the finger which is so formed that during the first portion of the rocking of the shaft, the finger is lifted into the type channel in advance of the type and thereafter the rocking of the shaft is independent of the finger. The movement of the finger is limited to the desired distance by the stop P which has shoulders p p' on opposite sides of the finger.

Extending above the two drums on the front side of the frame member z⁸ is an indicator V marked with characters corresponding to the type in the different rows in the supply drum. A pointer W is provided to coöperate with the characters on this chart and is connected by suitable mechanism with the supply drum. The mechanism may be a cable secured to the pointer and passing over the sheave S' (Fig. 3) at the left end of the frame members z⁷ and z⁸, and then down around a sheave on the supply drum. At the other end the cable, passes around the sheave s² and onto a spring barrel. The sheave on the supply drum is indicated by a³ in the diagrammatic view (Fig. 11), the cable by S, and the spring barrel by S². Suitable guide pulleys as S' may be provided for the cable. This cable indicator is more fully shown and claimed in the application of H. C. Gammeter No. 236,463, filed December 12th, 1904, above referred to.

It will be apparent that the actuation of either key causes the row of type in the channel of the corresponding drum which is opposite the transfer channel to be moved toward that channel, the foremost type passing into the channel. During the operation of assembling the line, the printing drum is stationary and the supply drum is turned by its crank to bring different channels into alignment with the transfer channel to assemble words—the position of the supply drum being indicated by the pointer W. During the distribution of a line the print-

ing drum is likewise stationary, the supply drum being turned to bring the proper channel into position according to the character on the face of the individual type in the line. The operation of distribution requires either considerable skill on the part of the operator in reading the characters or is comparatively slow. To enable the operation to be performed rapidly and without special skill in reading type, I provide an indicator adapted to show automatically the character of the individual type being distributed, whereby the operator may readily turn the supply drum to the desired position. This indicator which operates also as a copy holder and provides a character indication for use in assembling the type, is an essential part of the present invention.

The copy-holder, as shown, comprises a roller U journaled in a pair of arms u which engage and are supported by the upper end of the frame member z⁷. A suitable trough shaped plate u' connects the arms u and spring pressed rollers U' carried thereby provide the proper friction. In this copy holder, a sheet of the copy to be assembled may be inserted and is in convenient view to the operator, each successive line being turned up by the knob u⁸ on the shaft of the roller or in other manner.

In assembling the type, a copy of the matter to be printed is inserted in the copy holder. The follower block K is provided with a finger k³ which is adapted to coöperate with the copy on the copy holder, and the position of the copy holder relative to the pointer is adjusted, as hereinafter explained, so that the pointer continually indicates the character next to be set, so that the operator may see at once how to position the supply drum.

In distributing the type, a copy of the matter printed by the printing drum is inserted in the copy holder, whereby an exact reproduction is made of the type characters on the drum. The relative position of the copy holder and pointer is then adjusted so that the pointer indicates the character just about to pass into the supply drum, thereby enabling the operator to properly position it. This adjustment might be made in other manner, but it is simpler to make it by shifting the copy holder along its support,—the copy holder in the form shown being loosely mounted on the support to enable such shifting. If the transfer from the printing drum were directly to the supply drum, the copy holder and pointer k³ would be so relatively positioned that the indication would correspond to the foremost character on the type line in the printing drum. As however, several of the type are contained in the transfer channel during the distribution, the pointer is set a corresponding number of type behind the foremost character in the

line, so that it will indicate the character corresponding to the proper channel for the supply drum. My invention therefore is equally adaptable for use in assembling or distributing; in either case, the pointer stands opposite the character next to pass to or from the supply drum, whereby, in assembling, it forms a check on the operator, and in distributing, relieves him from the necessity of reading the type. In either case, all that is necessary is for the operator to turn the supply drum until its pointer W indicates the character on the scale V corresponding to the character indicated by the pointer k³ on the copy, and then to press the corresponding key f¹ or f².

A simple and satisfactory arrangement for providing the adjustment between the copy holder and the pointer k³ is to secure the copy holder slidably upon the frame member z⁷, the pointer being then rigid on the follower block. This may be accomplished by providing a bead z¹² along the upper edge of the frame member and arranging the arms u so that they extend over the beaded edge and embrace it freely enough to allow the copy holder to be shoved lengthwise thereof.

In order to prevent accidental displacement of the follower block K during the assembling of type, and enable this block to hold the type in a compacted line in the printing drum, I provide the follower block with a friction device. Since, however, there is sufficient friction from the type itself during the distribution, I arrange this additional friction to be applied only for movement of the block away from the transfer channel. This friction is provided by a roller k⁵ which occupies a slot in the rear wall of the follower and is pressed against the frame member z⁷ by a spring k⁶. This spring is inclined as shown in Fig. 9, so that the roller tends to jam against the frame member for rearward movement of the block, while in the forward movement the roller is freed.

Having thus described my invention, I claim:

1. The combination of a supply mechanism formed to carry individually movable type in rows, printing mechanism including a member formed to carry individually movable type in rows and a platen, means for advancing a row of the type as it is being assembled or distributed, and an indicator including means for holding a representation of the matter to be assembled or distributed and coöoperating means, one member of the indicator being automatically moved by the assemblage or distribution to show the character of the individual type required for assemblage into words or to be distributed from words.

2. The combination of a type holder, a

follower adapted to advance with the type therein, a pointer movable according to said follower, and a copy holder adapted to hold the copy in position for indication by the pointer.

5 3. The combination of a printing drum, a follower adapted to engage the type therein, a mechanism for advancing the follower, a pointer movable with the follower, and a copy holder adapted to carry copy in position for indication by the pointer.

10 4. In a duplicating machine, the combination of supply mechanism, printing mechanism, means for transferring type from one 15 to the other, an indicator adapted to show the character of the line of type in the supply mechanism at the transfer position and an indicator adapted to show the individual character of the type being transferred from 20 the printing mechanism to the supply mechanism.

25 5. In a duplicating machine, the combination of supply mechanism having type holders in which the type are arranged in rows of the same character, printing mechanism in which the type are assembled into words or numbers, the type being adapted to be transferred from the supply mechanism to the printing mechanism and vice versa, and 30 two indicators,—one to show the character of the different rows of type in the supply mechanism, and the other to show the individual character of the type in a row in the printing mechanism.

35 6. The combination of mechanism having longitudinal type holders, means for advancing a row of type in one of the holders to distribute it, a copy holder, and means co-operating therewith and movable with the 40 advancing type to indicate the character of individual type.

45 7. In a duplicating machine, the combination of a printing drum, a follower adapted to engage type therein, mechanism for moving the follower to distribute the type, a copy holder, a pointer carried by the follower and co-operating with the copy holder, and a finger key for operating the mechanism which moves the follower.

50 8. The combination of a member adapted to hold type, a follower adapted to engage such type, mechanism for moving the follower with the type, a copy holder, a pointer carried by the follower and co-operating 55 with the copy holder, and means for adjusting the relation of the copy holder and pointer.

55 9. The combination with supply mechanism, printing mechanism, a transfer channel between them, and means for transferring the type from the printing mechanism through such channel to the supply mechanism, or vice versa, said means including a follower adapted to engage said type 65 and guided to move parallel with the surface

of the printing mechanism, a copy holder, and a co-operating pointer movable according to the follower.

10 10. The combination of a printing drum and a supply drum placed end to end, a frame member between them having a transfer channel through it, an indicator connected with the supply drum and adapted to show the character of the row of type aligned with the transfer channel, a follower for the type in the printing drum, means for moving said follower toward the transfer channel, a pointer carried by said follower, and a copy holder adapted to carry a copy of matter printed by the printing mechanism, with which said pointer may co-operate to indicate the character on the individual type being distributed.

11 11. The combination of means for holding a line of type, a follower therefor, a friction device on the follower to prevent its accidental displacement and an indicator having a member carried by the follower to indicate the individual characters of the type.

12 12. The combination with printing mechanism including a platen and distributing mechanism, formed in a unitary structure, of an indication device having two members, one member of which corresponds to the matter printed, and means for moving one member of such device relative to the other member according to the distribution.

13 13. The combination of means for holding a line of assembled type, an indicator having two members, one of which is adapted to hold matter corresponding to such assembled type, and the other of which may co-operate with such matter, and means for concurrently advancing the line of type and correspondingly moving one of said members.

14 14. The combination of means for holding a line of assembled type, an indicator having two members, one of which corresponds as to order to such line, one of said members being movable with reference to the other, means for advancing the line of type, and means for concurrently moving said movable member.

15 15. The combination of a type holder, means for advancing lines of type therein, an indicator including a copy holding member and a co-operating member, one of which is movable, and means for moving said movable member concurrently with the advancement.

16 16. The combination of a type holder and follower adapted to advance with the type, a copy holder and a co-operating member, one of which is connected for movement with said follower.

17 17. The combination of a type holder, a follower adapted to advance with type in the type holder, a pointer connected for movement with the follower, and a copy

- holder adapted to hold copy in position for indication by the pointer.
18. The combination of means for holding a line of type, means for advancing such line by movements equal to the thickness of a type, an indicator having a member corresponding in order to the matter assembled or to be assembled and including a pointer movable by the advancing means. 5
19. The combination of a supply member having a series of type holders, means for moving said member, means for moving the type one at a time out of said holders, a copy holder, and a pointer coöperating therewith and adapted to be advanced by the assembled type. 10
20. The combination of means for holding a line of type, hand operated means for advancing such line for distribution, means operated automatically by such advancement for successively indicating the individual character of the type in such line, and means for receiving the individual type in lines of the same character. 15
21. The combination of means for holding a line of assembled type, means for advancing such line in the direction of the length of the line for distribution, and means operated automatically consequent upon such advancement for successively indicating the individual characters of the type in such line. 20
22. The combination of means for holding a line of assembled type, means for advancing such line for distribution, means for successively indicating the individual character of the type of such line, and a finger key for operating the advancing means, the indicating means operating automatically and consequent upon the actuation of the finger key. 25
23. The combination, with means for holding type, of key-operated means for assembling and distributing it, and two indicators, one adapted to show the character of lines of type and the other the character of individual type in the line. 30
24. The combination with type holding means, of a follower therefor, a retarding device acting on the follower and adapted to supply greater friction against the follower's movement in one direction than in the other and an indicator having two members, one of which is moved according to the movement of the follower. 35
25. The combination with a guide, of a follower slidable thereon, a roller, and a leaf spring pressing the roller against the guide, said roller being loosely mounted whereby it jams in one direction of movement of the follower, but not in the other. 40
26. The combination with a copy holder of a type follower having a pawl for engagement with the type and a pointer for coöperation with the copy holder. 45
27. The combination with a copy holder of a type follower having a pawl for engagement with the type, a pointer for coöperation with the copy holder, said follower having a tooth, and a type-advancing-comb adapted to engage such tooth. 50 70
28. The combination with a copy holder of a type follower having a pawl for engagement with the type, a pointer for coöperation with the copy holder, and a friction device for retarding the movement of the follower in one direction, but allowing it to move comparatively freely in the other. 55 75
29. The combination of a type holder adapted to carry a row of type, a movable member adapted to advance with such row of type in the holder, a pointer connected for movement with said member, and a copy holder adapted to hold copy in position for indication by the pointer. 80
30. The combination with type-holding means, of a movable end block for the type, means carried by such end block for supplying greater friction against the movement of such block in one direction than the other, a pointer carried by said end block and an indicating member with which the pointer coöperates. 85 90
31. The combination of means for holding a line of type, a follower movable with such type, a pointer carried by the follower, a finger key and mechanism operated thereby adapted to move the follower and type, and a copy holder adapted to hold copy in position for indication by the pointer. 95 100
32. The combination with a copy holder and a holder for a line of type, of a member adapted to move with such line, an indicating device moved to said member and adapted to coöperate with copy on the copy holder, a finger key, and mechanism controlled thereby for moving said type and member. 105
33. The combination of a drum adapted to hold lines of type, a frame member adjacent thereto, a movable follower slidable on said frame member, a copyholder carried by the frame member, and an indicating device coöperating with the copyholder and movable according to the movement of the follower. 110 115
34. In a duplicating machine, the combination of supply mechanism and printing mechanism, means for feeding the type from the printing mechanism toward the supply mechanism, said means including a movable follower, a pointed carried by said follower, and a copy holder adapted to carry copy with which the pointer coöperates. 120
35. In a duplicating machine, the combination of a supply drum and a printing drum placed end to end, a frame member extending longitudinally over the drums, a follower slidable upon said frame member and adapted to engage type on the printing 125 130

- 3 drum, a copyholder carried on the frame member, and a pointer movable with the follower and adapted to coöperate with copy on the copy holder.
- 5 36. The combination of supply mechanism, printing mechanism, type transferable between them, a follower for engaging the type, a pointer carried by the follower, and a coöperating copyholder, there being 10 a relative adjustment between the pointer and copyholder.
- 15 37. The combination of a supply member, a printing member, a member extending longitudinally thereof, a longitudinally guided follower, a copyholder carried by 20 said longitudinal extending member, and a pointer movable with the follower and adapted to coöperate with the copyholder.
- 25 38. The combination of a supply member and a printing drum placed end to end, a frame member extending longitudinally over the drum, a copyholder carried by said frame member, and a follower for the type carrying a pointer to coöperate with the 30 copyholder.
- 35 39. The combination of a supply drum, a printing drum placed end to end, a member extending longitudinally of said drums, a follower slidably guided by said member, and a copyholder mounted on said member and adapted to coöperate with said follower.
- 40 40. The combination of a supply drum and a printing drum placed end to end, a stationary member extending longitudinally over the drums, a follower for the type in the printing drum guided longitudinally on the underside of said stationary member, a copyholder mounted on said stationary member, and a pointer carried by the follower and coöperating with the copyholder.
- 45 41. The combination, with a supply drum, a printing drum, a member extending longitudinally thereof, a copyholder having 50 arms engaging said member, and a follower having a pointer to coöperate with the copy on said holder.
- 55 42. The combination, with a type channel, a printing drum, a member extending longitudinally thereof, a copyholder having arms engaging the said member, and a follower slidable along the lower edge of said member and having a pointer to coöperate with the copy of said holder.
- 60 43. The combination of a typeholder, a movable member adapted to advance with type therein, a pointer carried by the movable member, and a copyholder adapted to hold copy in position for indication by the pointer, said copyholder and pointer coöperating and one of them being bodily movable to allow the copy and pointer to be positioned with reference to each other.
- 65 44. The combination, with typeholding means, of a movable end block for the type, a pointer carried by such end block, and a copyholder adapted to carry copy in coöperation with the pointer, said copyholder and pointer coöperating and one of them being bodily movable in a path parallel with the path of movement of the block.
- 70 45. The combination of a movable printing member, a frame member extending parallel therewith, a copyholder mounted on the frame member, a movable end block adapted to engage type in the printing member and slidably mounted on said frame member, and a pointer carried by such block and adapted to coöperate with copy on the copyholder.
- 75 In testimony whereof, I hereunto affix my signature in the presence of two witnesses.
